No. 790,549.

PATENTED MAY 23, 1905.

W. BARTHOLOMEW.
EDGE SMOOTHING MACHINE.
APPLICATION FILED APR. 29, 1904.

UNITED STATES PATENT OFFICE.

WILLIAM BARTHOLOMEW, OF NEW YORK, N. Y., ASSIGNOR TO TROY LAUNDRY MACHINERY COMPANY, LIMITED, OF TROY, NEW YORK, A CORPORATION OF NEW YORK.

EDGE-SMOOTHING MACHINE.

SPECIFICATION forming part of Letters Patent No. 790,549, dated May 23, 1905.

Application filed April 29, 1904. Serial No. 205,612.

To all whom it may concern:

Be it known that I, WILLIAM BARTHOLOMEW, a citizen of the United States, residing at New York, in the county of New York, State of New York, have invented certain new and useful Improvements in Edge-Smoothing Machines, of which the following is a specification, reference being had therein to the accompanying drawings.

- 10 This invention relates to an edge-smoothing machine, and particularly to a structure adapted to smooth and iron the rough edges of a starched article after the preliminary ironing thereof.
- 15 In the laundering art collars, cuffs, neckbands, and other articles having starched edges if frayed or worn present a rough edge when stiffened by starching and the ordinary ironing operation; and the present invention has for its object to present this edge to a smoothing-surface having sufficient moisture to soften the rough edge and permit it to be ironed by contact with the heated face of the smoothing-surface as such an article is drawn or moved along such a surface. In order to prevent an excess of moisture, as well as the impingement of a direct jet of steam upon the article so treated, which would injure the finish thereof, means are provided in this
- 25 machine for obstructing the direct flow of the jet of steam, such means being preferably of an absorbent character and disposed to intercept the steam - passage extending from a steam-chamber to the smoothing-surface.
- 30 A further object of the invention is to provide guide-plates adjacent to the smoothing-surface adapted to facilitate the introduction and movement of the article in contact with said surface and one of said plates being suitably apertured to prevent the collection of moisture thereon and to retain it in a suitable cooled condition, so that it will not injure the surface of a starched and ironed article placed in contact therewith.
- 35 Other and further objects and advantages of the invention will be hereinafter set forth

and the novel features thereof defined by the appended claims.

In the drawings, Figure 1 is a perspective of the invention; Fig. 2, a central vertical section, and Fig. 3 a horizontal section through the steam-jet passages.

Like letters of reference refer to like parts in the several figures of the drawings.

The letter A designates a steam-chamber, 55 which may be of any desired construction or configuration—for instance, cylindrical, as shown—and provided with a base A' for conveniently supporting the same upon a table or other surface. The upper portion of this 60 chamber is provided with a threaded opening A², adapted to receive an interiorly-threaded nut A³, into which a steam-pipe A⁴ is threaded and projects downwardly through the steam-chamber into the discharge or drip pipe A⁵. 65 The steam-pipe is provided within the chamber A with a suitable outlet A⁶ to permit the discharge of dry steam into the chamber, while the steam discharged from the lower end of the pipe will also rise through the drain- 70 pipe into the chamber, and the moisture or water of condensation will be discharged from the feed-pipe directly into the drain. This drain-pipe may be supported from the chamber in any desired manner—for instance, by 75 means of the nut A⁷, threaded into an aperture A⁸ in the lower portion thereof and having an interiorly-threaded surface to receive the pipe A⁵.

Disposed at one side of the chamber A is a 80 smoothing-surface B, which may be of the desired configuration to accommodate the character of work to be performed thereon—for instance, slightly curved at its opposite ends B'—while extending inward from this smoothing-surface are a series of passages B², extending to and communicating with the steam-chamber A, so as to conduct a jet of steam from said chamber to the smoothing-surface. These passages may be disposed in any pre- 85 ferred manner; but as herein shown they are disposed radially to the center of the chamber 90

for the purpose of extending the heating area thereof over the entire smoothing-surface, thus maintaining the same at the desired temperature and also providing a smoothing-face 5 between the passages to perform an ironing function in the passage of an article across the face. The direct contact of a steam-jet with a starched and ironed article would destroy the finish thereof, and for that purpose an obstruction is disposed to prevent this direct flow and to diminish the degree of moisture which will be presented at the open end of the 10 passages. This obstruction may be secured by different means; but as showing a desirable 15 form thereof I have illustrated herein a chamber B³, extending transversely across and intercepting each of the passages, and within this chamber an obstructing medium is placed—such, for instance, as an absorbent-cotton 20 wick, as shown at B⁴—which retards the direct passage of the steam-jet and regulates the degree of moisture which can be applied to the edge of the article brought into contact with the smoothing-surface. For the purpose 25 of supporting this article in contact with the surface and properly guiding the same a lower supporting-plate C is provided, which is suitably apertured, as shown at C', for the purpose of retaining this plate at a lower temperature than the smoothing-surface and also 30 for preventing the collection of moisture thereon. The plate C is provided with a vertical wall C², adapted to abut against the lower face of the smoothing-surface B, and at each end 35 with a rearwardly-extending lug or ear C³ beneath said surface, the opposite ends C' of the plate being suitably curved or deflected downwardly to facilitate the introduction of an article between it and the upper plate D, which 40 is similarly deflected in an opposite direction at its ends D', as shown in Fig. 1. This upper guide-plate D is provided with a vertical flange D² and with rearwardly-extending lugs D³, through which and into the lugs C³ of the 45 lower plate extend suitable securing-screws D⁴, passing also through the body of the smoothing-face B.

In the operation of the invention the collar or other article to be smoothed is introduced 50 between the guide-plates, as shown by dotted lines in Fig. 2, and drawn longitudinally along the smoothing-surface in contact therewith. During this movement the moisture emitted from the steam-passages softens the starch 55 upon the edge of the article, which edge is immediately brought into contact with the heated face of the smoothing-surface between adjacent passages and an ironing function effected which restores the finish to the edge while 60 removing any projecting or roughened surfaces which frequently occur upon starched articles, particularly after they are worn to some extent.

It will be seen that the structure of steam-

cylinder permits the introduction of dry or 65 superheated steam therein and readily conducts therefrom any water or moisture which may be carried by the steam-pipe, so that the same will be drained into the discharge or exhaust pipe at the lower portion of the chamber. 70

It will be obvious that changes may be made in the details of construction and configuration of this invention without departing from the spirit thereof as defined by the appended 75 claims.

Having described my invention and set forth its merits, what I claim, and desire to secure by Letters Patent, is—

1. In an edge-smoothing machine, a smoothing-surface having a steam-conducting passage, and means located in said passage for obstructing the direct flow and diminishing the degree of moisture of steam passing through 80 said means.

2. In an edge-smoothing machine, a steam-chamber, a smoothing-surface having a passage communicating therewith, and absorbent means introduced into said passage to prevent the direct flow of steam to the smoothing-surface. 85

3. In an edge-smoothing machine, a steam-chamber, a smoothing-surface disposed at one side thereof and provided with a passage communicating with said chamber, and means intercepting said passage for obstructing the direct passage of the steam to said surface and diminishing the degree of moisture therein. 95

4. In an edge-smoothing machine, a steam-chamber, a smoothing-surface disposed at one side thereof and provided with a passage communicating with said chamber, means intercepting said passage to prevent the direct passage of steam to said surface, a guide-plate beneath said surface, and a coöperating guide-plate above said surface. 100

5. In an edge-smoothing machine, a steam-chamber, a smoothing-surface disposed at one side thereof and provided with a passage communicating with said chamber, means intercepting said passage to prevent the direct passage of steam to said surface, a guide-plate beneath said surface, and a coöperating guide-plate above said surface, the opposite ends of 110 said plates being curved away from each other.

6. In an edge-smoothing machine, a steam-chamber, a smoothing-surface disposed at one side thereof and provided with a passage communicating with said chamber, means intercepting said passage to prevent the direct passage of steam to said surface, a guide-plate beneath said surface, a coöperating guide-plate above said surface, the opposite ends of said plates being curved away from each other, lugs projecting from said plates toward the smoothing-surface, and securing means extending through said lugs and body of the smoothing-surface. 115

7. In an edge-smoothing-machine, a steam-

chamber, a smoothing-surface having a series of passages extending to said chamber, and a packing-chamber extending longitudinally of the smoothing-surface and provided with a packing to obstruct the direct flow of the steam through said passages.

8. In an edge-smoothing machine, a steam-chamber, a smoothing-surface upon a side wall of said chamber and having a series of 10 passages extending to said chamber, a packing-chamber extending longitudinally of the smoothing-surface and provided with a packing to obstruct the direct flow of steam through said passages, a discharge-pipe at the lower 15 portion of said steam-chamber, and a steam-pipe extending through said chamber into the discharge-pipe and provided within the chamber with discharge-openings.

9. In an edge-smoothing machine, a steam-chamber, a smoothing-surface having a series 20 of passages extending to said chamber, a packing-chamber extending longitudinally of the smoothing-surface and provided with a packing to obstruct the direct flow of steam through 25 said passages, a discharge-pipe at the lower portion of said steam-chamber, a steam-pipe extending through said chamber into the discharge-pipe and provided within the chamber with discharge-openings, a lower apertured 30 supporting-plate at one side of the smoothing-surface, and a coöperating plate at the opposite side of the smoothing-surface.

10. In an edge-smoothing machine, a steam-chamber, a smoothing-surface having passages 35 communicating with said chamber and ironing-faces between said passages and means located in said passages for obstructing the direct flow and diminishing the degree of moisture of steam passing therethrough.

40 11. In an edge-smoothing machine, a smoothing-surface comprising dampening and ironing means, a steam-chamber having a passage communicating with said surface, means

located in said passage for obstructing the direct flow and diminishing the degree of moisture of steam passing therethrough, a discharge-pipe at the lower portion of said chamber, and a feed-pipe extending downward through said chamber and discharging into said discharge-pipe and having steam-outlets 50 within the chamber.

12. In an edge-smoothing machine, a steam-chamber, a smoothing-surface having communication with said chamber, an apertured supporting-plate extending parallel with said surface, and a coöperating guide-plate extending parallel to the supporting-plate.

13. In an edge-smoothing machine, a steam-chamber, a smoothing-surface having passages 55 communicating with said chamber and provided with a longitudinal groove or channel curved inward at its opposite ends and means located in said passages for obstructing the direct flow and diminishing the degree of moisture of steam passing therethrough.

14. In an edge-smoothing machine, a steam-chamber, a smoothing-surface having a series 60 of passages disposed radially to the center of said chamber, a laterally-disposed packing-chamber intermediate of the ends of said passages, and a packing within said packing-chamber.

15. In an edge-smoothing machine, a steam-chamber, a smoothing-surface having a series 75 of passages disposed radially to the center of said chamber, a packing-chamber disposed to intercept said passages, and an absorbent fibrous packing disposed within said packing-chamber to obstruct the direct flow of steam through said passages.

In testimony whereof I affix my signature in presence of two witnesses.

WILLIAM BARTHOLOMEW.
